W. J. STOOP

APPARATUS FOR AND METHOD OF FORMING AND HANDLING SHEET BARS AND THE LIKE

Filed Dec. 13, 1922

UNITED STATES PATENT OFFICE.

WILLIAM J. STOOP, OF WHEELING, WEST VIRGINIA.

APPARATUS FOR AND METHOD OF FORMING AND HANDLING SHEET BARS AND THE LIKE.

Application filed December 13, 1922. Serial No. 606,598.

To all whom it may concern:

Be it known that I, WILLIAM J. STOOP, a citizen of the United States of America, and resident of Wheeling, county of Ohio, and State of West Virginia, have invented 5 certain new and useful Improvements in Apparatus for and Methods of Forming and Handling Sheet Bars and the like, of which the following is a specification.

10 This invention relates broadly to a sheet-bar rolling and handling system, and more specifically to an apparatus for and a system or method of rolling, treating and handling sheet bars.

15 It has been the general and practically universal practice heretofore to pile sheet bars in stacks immediately following the rolling thereof and while said bars are still heated to a very high temperature. Such 20 stacking, commonly termed "hot piling", invariably results in a reduction of the carbon content of the bars and frequently results in complete decarbonization of the surfaces of the bars, and, further, results in 25 enlarging or coarsening the surface grain of the metal. In such hot piling the carbon is furnished oxygen by the scale on the surface of the bar, and this scale is reduced to a lower oxide of such harder 30 nature that it is caused to cling or adhere very closely to the surface, with the result that it bakes on the bar instead of cracking off. This condition of the bar, instead of being improved in reheating, is 35 aggravated, each subsequent heating acting to enlarge or coarsen the grain, the bars being rarely heated to grain-reconstruction temperature in such reheating, or even in box annealing. Additionally, the bar shows 40 an imperfect surface finish due to the hot rolling strains. Sheets rolled from such hot-piled bars accordingly retain scale pittings and other surface inequalities and imperfections of the bars, rendering their surfaces rough and extremely difficult to polish, and also requiring an excessive amount 45 of tin and spelter coating for the production of tin plate and galvanized sheets.

By my present invention the bars are 50 handled and treated in such manner that the quality of the metal is improved, much of the scale is removed from the bars, and the reduction of the carbon in the surfaces of the bars is very largely prevented, resulting in said bars possessing relatively 55 smooth and fine grained surfaces. When these bars are reheated, such scale as remains thereon is cracked off as a result of the expansion which occurs, leaving the bars practically clean and affording a greatly improved working surface. Sheets rolled from these bars are of highest grade both in quality and appearance and are admirably adapted for deep drawing purposes—that is, for use in the manufacture of hollow sheet metal ware or articles produced by deep drawing processes. They possess a dense, smooth and practically perfect surface finish, and are capable of being readily polished and also being smoothly coated 60 in tinning or galvanizing with a marked saving in the quantity of the coating material employed. Further, the sheets have fine grain structure, do not indicate surface decarbonization and do not possess the 65 usual oxide enclosures.

Thus, it is the primary object of this invention to provide, in association with a bar mill, a series of mechanisms arranged in such relation that the sheet bars from 70 said mill are individually handled to effect prompt cooling thereof without coming into direct contact one with the other.

A further object is to provide a mill for 75 rolling sheet bars having associated therewith a bar-cooling bed and intermediate automatic mechanisms whereby, in a continuous series of operations occurring in proper sequence, the metal emerging from the delivery roll of the mill is sheared into 80 bar lengths and said lengths are individually handled to effect boshing, air cooling and final piling thereof.

A still further object is to provide apparatus whereby sheet bars are produced 85 and handled in an expeditious and wholly automatic manner from the time they are rolled until piled in orderly form and in fully cooled condition at a point remote from the rolling point.

In describing the invention in detail, 90 reference is herein had to the accompanying drawings, in which—

Figure 1 is a diagrammatic view of my invention, illustrating the preferred relative arrangement of the individual mechanisms; 95

Figure 2 is a partial diagrammatic view showing the bosh and flying shear occupying relative positions the reverse of those shown in Fig. 1;

100

105

110

Figure 3 is a view similar to Fig. 1 with the bosh omitted;

Figure 4 is a view similar to Fig. 1 showing the cooling bed omitted; and

5 Figure 5 is a view similar to Fig. 2 showing the cooling bed omitted.

Referring to said drawings, 1 indicates the final, or delivery set, of rolls of a mill employed in the rolling of sheet bars, said 10 set being preferably the final set of a mill of continuous type, generally designated in Fig. 1 by the reference character A. Emerging from said rolls 1 at high speed, the long strip of reduced metal passes from 15 the mill to a set of pinch rolls 2 located in the line of its travel. In the arrangement which is at present preferred, said pinch rolls 2 are located between a flying shear 3 and a boshing tank 4, said shear being 20 preferably located adjacent to said rolls 1, and the bosh at the opposite side of said pinch rolls, as shown in Figs. 1 and 4, but the relative positions of the shear and the bosh may be reversed, as shown in Figs. 25 2 and 5. Said flying shear acts to cut or shear the advancing reduced ingot into bar lengths without interfering with or retarding the advance movement of the metal, and whether said shear occupies the position relative to the bosh shown in Figs. 1 and 4, or that shown in Figs. 2 and 5, the metal, traveling at high speed and at the final bar-rolling temperature, is promptly plunged 30 into the cold water of the bosh. Said bosh, which is preferably of the form disclosed 35 in my co-pending application for patent, Serial No. 560,587, is made of such short length that the metal is submerged therein but momentarily, the purpose being to effect 40 a sudden, but not too great, reduction in the temperature of the bars. More specifically stated, it is designed that the temperature of the bars shall be reduced to a substantial extent by water cooling while said bars are 45 still in rapid motion. Such partial reduction of temperature may be effected without undue distortion of the bars, whereas such distortion would occur were the bars to remain submerged in the bosh until fully 50 cooled. In this sudden initial cooling and the rapid forward travel of the bar through the bosh, much of the scale carried by the bars is removed.

In the arrangement shown in Fig. 1, the 55 bars upon leaving the bosh are immediately caught by pinch rolls 5 whereby they are advanced to a transfer table B from which they are shifted to the traveling conveyors of an air-cooling bed C, said transfer table 60 and said cooling bed being of the general character disclosed in my said co-pending application. Said bars are advanced on said conveyors and are delivered therefrom to a carrying-off table D embodying travel- 65 ing rollers 6 upon which they are conveyed

forward to a set of pinch rolls 7, whence they are advanced to a bar piler 8 which may be of any approved type.

The conveyors of the cooling bed, even when advanced at maximum speed, transport the partially cooled sheet bars delivered thereto so slowly that, when the bar piler is reached, the heat thereof is dissipated in the air to the extent that no alteration in the physical character of the surfaces of the bars due to the remaining heat can occur following piling of the bars.

In the modification shown in Fig. 3, in which the bosh is omitted, it is designed 80 that cooling of the bars shall be wholly accomplished in the travel of the air-cooling bed.

In Fig. 4 a plurality of alined boshing tanks into which the bars are successively plunged are employed, and the air cooling 85 bed is omitted, the bars being passed directly from the final bosh 4' to the bar piler 8.

In Fig. 5 the shear is located for shearing the bars following boshing, and the bars 90 are thence passed directly to the bar piler, the air cooling bed being omitted.

While any of the combinations disclosed, and with the elements arranged as, in Figs. 95 3, 4 and 5 may be employed, and each is productive of improved results as compared with the prevailing practice of hot piling, it is at present considered that the best results are obtainable through the combined use of bosh cooling and air cooling attained 100 either by the arrangement shown in Fig. 1 or by that shown in Fig. 2.

While sheet bars have herein been specifically referred to as the material acted upon, 105 it is obvious that any similarly rolled sections of material may be treated successfully by this method.

What is claimed is—

1. In a continuous sheet-bar forming and handling apparatus, the combination with a mill for reducing the metal, of a flying shear located for shearing the reduced metal into bar form as it advances from said mill, a boshing tank located in alinement with the path of travel of the bars, means for advancing said bars through said tank, a bar piler, and means for advancing the boshed bars to said bar piler.

2. In a continuous sheet-bar forming and handling apparatus, the combination with a mill for reducing the metal, of a flying shear located for shearing the reduced metal into bar form as it advances from said mill, a boshing tank located in alinement with the path of travel of the bars, means for advancing said bars through said tank, a bar piler, and an air cooling bed intermediate 120 said boshing tank and said bar piler, said cooling bed embodying means by which the 125 bars are advanced.

3. In a continuous sheet-bar forming and handling apparatus, the combination with a mill for reducing the metal, of a flying shear located for shearing the reduced metal into bar form as it advances from said mill, a bar piler, means intermediate the shears and said bar piler for successively cooling said bars in their travel to said bar piler, said means including devices for successively and separately advancing said bars to said bar piler, and means for delivering said bars to said cooling means.
4. In a continuous sheet-bar forming and handling apparatus, the combination with a mill for reducing the metal, of a flying shear located for shearing the reduced metal into bar form as it advances from said mill, a bar piler, a cooling bed embodying advancing carrying devices, means for advancing the bars following shearing and for delivering the same to said bed, and means for advancing said bars from said bed to said bar piler.
5. In a continuous sheet-bar forming and handling apparatus, the combination with a continuous bar mill, of a boshing tank located adjacent to said mill and through which the reduced metal is directed in its travel from said mill, a flying shear whereby said reduced metal is sheared into bar lengths, air-cooling means for said bars, means for delivering the sheared bars to said air-cooling means, a bar piler, and means for advancing said bars from said air-cooling means to said bar piler.
6. In a continuous sheet-bar forming and handling apparatus, the combination with a continuous bar mill, of a boshing tank located adjacent to said mill and through which the reduced metal is directed in its travel from said mill, a flying shear whereby said reduced metal is sheared into bar lengths, a bar piler, and means for advancing the sheared bars to said bar piler.
7. A continuous bar forming and handling apparatus, comprising a bar mill for reducing the metal to bar section, shears for cutting the bar section to bar lengths while in motion, conveyors for effecting cooling of such bars while in motion, and means for piling said bars.
8. The method of producing and automatically handling sheet bars, which consists in rolling the metal into bar form, passing the reduced metal through a boshing tank, shearing said metal into bar lengths, delivering said bars to transporting devices, advancing said bars on said devices, and finally piling the cooled bars.
9. The method of producing and automatically handling sheet bars, which consists in cutting the metal into bar lengths as it passes from the reducing rolls, passing the bars individually through a boshing tank, delivering said bars to transporting devices, advancing said bars on said devices for separately air-cooling the same, and finally piling the cooled bars.
10. The method of producing and automatically handling sheet bars, which consists in successively rolling the metal into bar form, shearing said metal into bar lengths as it passes from the reducing roll, passing the bars individually through a boshing tank, and then subjecting said bars individually to further cooling by air.
11. The method of producing and automatically handling sheet bars, which consists in successively rolling the metal into bar form, shearing said metal into bar lengths as it passes from the reducing rolls, and then passing the bars individually through a boshing tank to effect a substantial reduction of temperature.
12. The method of producing and automatically handling sheet bars, which consists in successively rolling the metal into bar form, passing the reduced metal through a boshing tank, shearing said metal into bar lengths, then effecting a further reduction in the temperature of said bar by air-cooling, and finally piling the cooled bars.
13. The method of producing and handling bars, which consists in successively rolling the metal into bar form, shearing said metal into bar lengths, passing the bars through a boshing tank to effect a reduction of temperature, and then advancing the bars from said tank for effecting further reduction of temperature by air cooling.
14. A continuous bar forming and handling apparatus comprising a bar mill for reducing the metal to bar section, shears for cutting the bar section to bar lengths, and means for momentarily submerging said bars in a cooling bath.
15. A continuous bar forming and handling apparatus, comprising a bar mill for reducing the metal to bar section, shears for cutting the bar section to bar lengths, and a boshing tank through which the bars are separately advanced for effecting partial cooling of the latter through immersion in a cooling liquid.
